CLAIM

The ornamental design for a heater for semiconductor thermal process, as shown and described.

DESCRIPTION

FIG. 1 is a front, top, right side perspective view of a heater for semiconductor thermal process showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dashed-dot-dashed lines represent the boundary lines of the claimed design.

The broken lines shown in the drawings represent portions of the heater for semiconductor thermal process that form no part of the claimed design.

1 Claim, 4 Drawing Sheets
